HILMER N. ENHOLM, OF BURLINGTON, IOWA, ASSIGNOR, BY DIRECT AND MESNE ASSIGNMENTS, TO WEATHER-PROOF WATERING TROUGH AND TANK MFG. CO., INC., OF BURLINGTON, IOWA.

MOLD FOR WEATHERPROOF WATERING-TROUGHS.

1,251,650.

Specification of Letters Patent.

Patented Jan. 1, 1918.

Application filed July 6, 1917. Serial No. 178,945.

To all whom it may concern:

Be it known that I, HILMER N. ENHOLM, a citizen of the United States, residing at Burlington, in the county of Des Moines 5 and State of Iowa, have invented certain new and useful Improvements in Molds for Weatherproof Watering-Troughs, of which the following is a specification.

This invention relates to improvements in 10 molding devices whereby tanks and like receptacles of various shapes and sizes may be constructed with hollow walls, or with walls having dead air spaces therein, and has for one of its objects to provide a device of this 15 character constructed of sheet or plate metal and in separable sections, or partly of metal and partly of wood, and capable of being increased or decreased in size by increasing or decreasing the number of the sections. 20 Another object of the invention is to provide a device of this character which may be transported from place to place and employed in constructing tanks or like receptacles where they are to remain permanently, 25 and which may be repeatedly employed for constructing the tanks in any required locality.

With these and other objects in view, the invention consists in certain novel features 30 of construction, as hereinafter shown and described and then specifically pointed out in the claims; and in the drawings illustrative of the preferred embodiment of the invention—

35 Figure 1 is a plan view partly in section of one of the improved molds;

Fig. 2 is a transverse section on the line 2—2 of Fig. 1 illustrating the manner of 40 erecting the mold units and utilizing the same to produce the tank or like receptacle;

Fig. 3 is a transverse section of the completed tank;

Fig. 4 is a perspective view of a portion 45 of the improved mold device, illustrating the manner in which the parts are supported in relative position;

Fig. 5 is a sectional detail illustrating a modification in the construction;

Fig. 6 is a sectional detail illustrating another modification in the construction.

Corresponding and like parts are referred to in the following description and indicated in all the views of the drawings by the same reference characters.

The improved device comprises in general 55 an outer shell, an inner shell, an outer intermediate shell and an inner intermediate shell disposed in spaced relation, the space between the outer shell and the outer intermediate shell designed to receive cementitious material and forming the outer wall of the tank or trough, and the space between the inner shell and the inner intermediate shell designed to receive cementitious material to form the inner wall of the 60 tank or trough, a dead space between the intermediate shells constituting the air space between the walls of the trough or tank.

The shells are constructed in a plurality of sections engaging end to end, and may be 70 of any required form or shape to conform to the tanks or troughs which it is required to construct, and it is not desired to limit the invention in any manner to the size or form of the tank or trough. For the purpose of 75 illustration a molding apparatus is shown arranged to form an oblong tank having rounded or semi-circular ends, which is the usual form. The terminal portions of the various shells will preferably be constructed 80 of sheet or plate metal as light as possible consistent with the strains to which they will be subjected, and will preferably be galvanized or otherwise protected from corrosion, while the side portions of the shell 85 sections will preferably be of wood in stave form as shown in Fig. 5, or all of the sections may be of wood or all of metal as may be found most advantageous. The outer terminal shell sections are designated by the 90 character 10, while the intermediate outer shell sections are designated by the character 11. The terminal sections of the outer intermediate shell are designated by the character 12, while the side sections of the 95 outer intermediate shell are designated by the character 13. The terminal sections of the inner intermediate shell are designated by the character 14, while the side sections of the inner intermediate shell are designated by the character 15. The terminal sections of the inner shell are designated by the character 16, while the side sections of the inner shell are designated by the character 17. The various sections 10—11 are of 100 the full height of the tank or trough which is to be constructed, the outer intermediate shell sections are of less height than the

outer shell sections, the inner intermediate shell sections are of less height than the outer intermediate shell sections, while the inner shell sections are of the same height as the 5 inner intermediate shell sections, the reason for these differences in height to be hereafter explained.

The ends of the several side sections next to the terminal sections are provided with 10 vertical combined guard and holding members 18, preferably of L metal, which overlap the joints between the sections. When two or more of the side sections are employed to increase the length of the tank or trough, the 15 adjacent webs of the members 18 are coupled by plates 19 bolted or otherwise secured in place. By furnishing a plurality of the side sections of different widths having the guard members 18 attached, together with a corresponding number of the coupling members 19, tanks or troughs of different lengths may be produced, as will be obvious.

The various sections are also provided with horizontally directed supporting or 20 bracing ribs 20. The ribs are located upon the outer faces of the outer sections 10-11, upon the inner faces of the inner sections 16-17, and upon the confronting faces of the intermediate sections 12-13 and 14-15. 25 The ribs 20 abut at their ends against the edges of the members 18. The ribs 20 are preferably formed of L-bars with one web of each rib directed laterally from the section to which it is attached, and all of the 30 brace members 18 and ribs 20 are firmly riveted or otherwise secured to the sections. The ribs 20 of the outer and inner sections are coupled near their ends by stays 21 and each stay provided with a clip device 22 to 35 receive the hooked terminal 23 of a binding rod 24, by which the sections are firmly held in position. Each binding rod is provided with a turn-buckle 25, to enable the requisite strain to be imparted to hold the parts together and to take up any slack which may occur. By this means an effectual coupling means is provided whereby the various sections are held in position and prevented from displacement. Transverse braces or 40 tie members 26 are provided to extend over the joints between the terminal sections and the side sections and are formed with downwardly directed terminals 27 which are bolted or otherwise secured to the members 18, as shown in Fig. 1. Other stay members, one of which is indicated at 28, are connected at their ends respectively to the stays 26 and to the terminal shell members 10. Depending from the stays 26 are vertical 45 stay members 29 which are bolted or otherwise secured to the intermediate and inner sections, to hold them in proper spaced position.

A set of the stay devices will be located at 50 each end of the mold apparatus and at as

many intermediate points as required, but one set only is shown in Figs. 1 and 2, to avoid obscuring the details of construction.

The retaining member upon which the inner bottom member is supported is represented at 30, and is suitably supported by spacer blocks 31 whereby the member 30 is supported in spaced relation to the lower bottom member or base designated at 36. Other spacer blocks 33 are located between the intermediate shell members at their lower ends as shown in Fig. 2. The retaining member which is located over the upper edges of the cementitious side walls is designated by the character 34.

As many of the spacer members 33 may be employed as required and spaced any suitable distance.

With a device thus constructed the various steps required to construct the tank or trough 55 is as follows:

The outer shell sections 10-11 are erected where the tank is to be located with their lower edges upon the ground and the coupling rods 24 with their turn-buckles applied.

The required number and sizes of the side members 11, 13, 15 and 17 are employed to form the required size of trough and are connected as above described.

A layer of cementitious material is then deposited upon the ground within the sections 10-11 and leveled off by suitable implements. This layer of material constitutes the outer or lower bottom member 36 of the 100 tank or trough. The outer intermediate sections 12-13 are then erected within the outer shell sections and spaced inwardly therefrom with their lower edges resting upon the bottom member 36. The spacer blocks 33 are then located in position upon the lower bottom member 36 as shown in Fig. 2, and the spacer members 31 likewise disposed in position and the retaining member 30 deposited upon the spacer members.

The inner intermediate section members 12-13 are then located in position within the outer intermediate shell sections and spaced therefrom and against the spacer blocks 33. The stay members 26 and 28 are then arranged in position and coupled to the outer shell members and the intermediate stay members 29 coupled to the outer intermediate shell members. Another layer of cementitious material indicated at 32, is then deposited upon the retaining member 30 and leveled off by a suitable implement. The inner section members 16-17 are then located in position and spaced from the inner intermediate sections 14-15, and the stay members 29 coupled thereto. The space between the outer sections 10-11 and the inner intermediate sections 12-13 is then filled with cementitious material and the space between the inner section numbers 130

15—17 and the inner intermediate sections 14—15 likewise filled with the cementitious material, the two vertical sections of the material constituting the side walls of the 5 tank or trough which terminate at the upper edges of the intermediate sections. After the material has sufficiently "set" the intermediate sections are removed, and the spacer blocks 33 likewise removed if required. The 10 retaining members 34, which are preferably of suitable screen material like the member 30, are then deposited upon the upper edges of the side walls just constructed, and the space between the member 34 and the upper 15 edges of the outer and inner shell sections filled with cementitious material indicated at 37. The outer and inner shell sections are then removed leaving the tank complete with a dead air space between the vertical 20 walls and the closure portion 37.

The various mold units may be cheaply and strongly constructed and the parts readily separated for shipment or storage or to enable the tank or trough to be erected in 25 any required locality, or a plurality of the tanks erected in close proximity, the mold units being adapted for use repeatedly, as will be obvious.

The spacer members 31 may be in the form 30 of hollow brick represented at 38 in Fig. 6, and the base portion 36 may likewise be in brick-like form, as shown in the same figure.

Having thus described the invention, what 35 is claimed as new is:

35 1. A molding apparatus of the class described comprising an outer shell adapted to bear upon a supporting base, an inner shell spaced at its lower edge from the support and in transverse alinement at its upper edge with the upper line of the outer shell, an outer intermediate shell spaced from the outer shell and spaced at its upper and lower edges respectively above the support and below the line of the upper edge 40 of the outer shell, an inner intermediate shell spaced from the inner shell with its upper edge in transverse alinement with the upper edges of the outer intermediate shell and extending at its lower edge above the line of the lower edge of the outer intermediate shell, a retaining member adapted to be disposed between the outer and inner shells and below the upper line of the same, stay members engaging the inner shell, and stay members engaging the several shells 45 and holding them in spaced relation.

4. A molding apparatus comprising an outer shell of a plurality of sections engaging end to end and adapted to bear upon a supporting base, an inner shell of a plurality of sections engaging end to end and spaced at their lower edges from the support and in transverse alinement at their upper edges with the upper lines of the sections of the outer shell, an outer intermediate shell of 50 a plurality of sections engaging end to end and spaced from the sections of the outer shell and spaced at their upper and lower edges respectively above the support and below the lines of the upper edges of the outer shell, an inner intermediate shell of 55 a plurality of sections engaging end to end and spaced from the sections of the inner shell with their upper edges in transverse alinement with the upper edges of the sections of the outer intermediate shell and extending at their lower edges above the lines of the lower edges of the sections of the outer intermediate shell, supporting ribs attached to the outer faces of the sections 60

65 intermediate shell of a plurality of sections engaging end to end and spaced from the sections of the outer shell and spaced at their upper and lower edges respectively above the support and below the lines of the upper edges of the outer shell, an inner intermediate shell of a plurality of sections engaging end to end and spaced from the sections of the inner shell with their upper edges in transverse alinement with the upper edges of the sections of the outer intermediate shell and extending at their lower edges above the lines of the lower edges of the sections of the outer intermediate shell, and a retaining member adapted to be disposed between the outer and inner shells and below the upper line of the same, said shell sections adapted to receive cementitious material between them and above the retaining member.

3. A molding apparatus of the class described comprising an outer shell adapted to bear upon a supporting base, an inner shell spaced at its lower edge from the support and in transverse alinement at its upper edge with the upper line of the outer shell, an outer intermediate shell spaced from the outer shell and spaced at its upper and lower edges respectively above the support and below the line of the upper edge of the outer shell, an inner intermediate shell spaced from the inner shell with its upper edge in transverse alinement with the upper edges of the outer intermediate shell and extending at its lower edge above the line of the lower edge of the outer intermediate shell, a retaining member adapted to be disposed between the outer and inner shells and below the upper line of the same, stay members engaging the inner shell, and stay members engaging the several shells 100 and holding them in spaced relation.

4. A molding apparatus comprising an outer shell of a plurality of sections engaging end to end and adapted to bear upon a supporting base, an inner shell of a plurality of sections engaging end to end and spaced at their lower edges from the support and in transverse alinement at their upper edges with the upper lines of the sections of the outer shell, an outer intermediate shell of 110 a plurality of sections engaging end to end and spaced from the sections of the outer shell and spaced at their upper and lower edges respectively above the support and below the lines of the upper edges of the outer shell, an inner intermediate shell of 115 a plurality of sections engaging end to end and spaced from the sections of the inner shell with their upper edges in transverse alinement with the upper edges of the sections of the outer intermediate shell and extending at their lower edges above the lines of the lower edges of the sections of the outer intermediate shell, supporting ribs attached to the outer faces of the sections 120

125 5. A molding apparatus comprising an outer shell of a plurality of sections engaging end to end and adapted to bear upon a supporting base, an inner shell of a plurality of sections engaging end to end and spaced at their lower edges from the support and in transverse alinement at their upper edges with the upper lines of the sections of the outer shell, an outer intermediate shell of 130

of the outer shell to the inner faces of the sections of the inner shell and to the confronting faces of the sections of the intermediate shells, said ribs being spaced at 5 uniform distances from the edges of the shell sections to enable the shell sections to be reversed in position, means applied to said ribs for coupling the shell sections together, and a retaining member adapted to 10 be disposed between the outer and inner shells and below the upper line of the same, said shell sections adapted to receive cementitious material between them and upon the retaining member.

15 5. The method herein described for constructing a tank consisting in depositing a layer of cementitious material upon a suitable foundation to constitute a lower bottom member, supporting a sustaining member in 20 spaced relation to the lower bottom member, depositing a layer of cementitious material upon the retaining member to constitute the inner bottom member, erecting an outer vertical wall of cementitious material upon 25 the lower bottom member, erecting an inner wall of cementitious material upon the inner bottom member and spaced from the outer wall, supporting a sustaining member upon the outer and inner walls, and depositing a

layer of cementitious material upon the last 30 mentioned sustaining member to constitute a closure to the space between the walls.

6. A molding apparatus of the class described comprising an outer shell, a lower retaining member, means for supporting 35 said lower retaining member above the lower line of the outer shell, an inner shell spaced at its lower edge above the lower retaining member and in transverse alignment at its upper edge with the upper line of the outer 40 shell, an outer intermediate shell spaced from the outer shell and spaced at its upper and lower edges respectively above the lower line and below the line of the upper edge of the outer shell, an inner intermediate shell 45 spaced from the inner shell with its upper edge in transverse alignment with the upper edge of the outer intermediate shell and extending at its lower edge above the line of the lower edge of the outer intermediate shell, and an upper retaining member adapted to be disposed between the outer and inner shells and below the upper line of the same, said shells adapted to receive cementitious material between them and above the 50 retaining members.

In testimony whereof I affix my signature.
HILMER N. ENHOLM. [L. s.]
